UNITED STATES PATENT OFFICE.

JAMES R. CARMER AND WILLIAM S. HUKILL, OF WILMINGTON, DELAWARE.

FLUID STORING AND TRANSPORTING RECEPTACLE.

No. 906,381.

Specification of Letters Patent.

Patented Dec. 8, 1908.

Application filed January 25, 1908. Serial No. 412,655.

To all whom it may concern:

Be it known that we, JAMES R. CARMER and WILLIAM S. HUKILL, citizens of the United States, residing at Wilmington, in the county of Newcastle and State of Delaware, have invented new and useful Improvements in Fluid Storing and Transporting Receptacles, of which the following is a specification.

10. This invention relates to fluid storing and transporting receptacles, and the object thereof is to provide a receptacle of such class with means in a manner as hereinafter set forth for automatically closing the intake and outlet opening of the receptacle to prevent any wash or slither of the fluid from passing through the opening to any material extent, said means further set up as to be automatically shifted from closing position when it is desired to discharge the contents of the receptacle.

15. Further objects of the invention are to provide a fluid storing and transporting receptacle which shall be simple in its construction, strong, durable, efficient in its use, and inexpensive to manufacture.

20. With the foregoing and other objects in view, the invention consists of the novel construction, combinations and arrangements of 30 parts hereinafter more specifically described and illustrated in the accompanying drawings wherein is shown the preferred embodiment of the invention, but it is to be understood that changes, variations and modifications can be resorted to which come within the scope of the claims hereunto appended.

25. In the drawings:—Figure 1 is a sectional side elevation of a receptacle in accordance with this invention, the outlet and intake openings being closed. Fig. 2 is a like view showing the position of the closing devices for the outlet and intake opening when filling the receptacle. Fig. 3 is a view similar 35 to Fig. 1, showing the position of the receptacle when discharging the contents therefrom. Fig. 4 is a view similar to Fig. 1 of a modification.

30. Referring to the drawings in detail, 1 denotes the body portion of the receptacle having a flat top 2, the latter being provided with an opening 3, the wall of said opening depending within the body portion forming thereby an annular flange 4 which gradually decreases in diameter inwardly and constitutes a valve seat for a globular valve 5,

the latter being positioned in a spout which is generally referred to by the reference character 6 and is adapted to close the opening 3, said opening 3 constituting an intake 60 as well as an outlet opening.

35. The spout 6 is vertically disposed with respect to the top 2 and is formed with a laterally extending flange 7 at its bottom through which extend hold-fast devices 8 65 for securing the spout 6 to the top 2. The spout 6 surrounds the opening 3 and is closed at its top with the exception of an opening 9 provided at the rear of the top and said spout is furthermore provided in its front 70 wall with a pocket 10, the wall of which depends downwardly at an inclination, the said pocket 10 being adapted to receive the valve 5 when the receptacle is tilted during the act of discharging the contents therefrom, as clearly shown in Fig. 3. The inclined wall 11 further constitutes a means upon which the valve 5 can be shifted during the act of filling the receptacle. This is clearly shown in Fig. 2 as the lower end 12 80 of the funnel 13 has shifted the valve 5 to one side of the opening 3 and upon the inclined portion 11. When filling the receptacle, the funnel extends down through the opening 9, as clearly shown in Fig. 2. The 85 spout 6 is furthermore provided with a hollow curvilinear cylindrical extension 14 which constitutes an outlet. The opening for the funnel is directly over the valve seat formed by the flange 4 and the attachment has a laterally extending pouring nozzle. To the body portion 1 is secured the apertured ears 15 to which is attached the bail 16, as clearly shown in Fig. 3.

40. From the foregoing arrangement of parts, it is evident that when the receptacle is in an upright position, the valve 5 will engage the seat 4, consequently closing the opening 3 and thereby prevent any wash or slither from the fluid to any extent from entering the spout 6. The valve 5 also constitutes means for closing the opening 3 so as to prevent the entrance of foreign matter to the interior of the receptacle. The weight of the valve 5 is such as to cause it to normally 45 maintain its seat, unless the receptacle is tilted or the valve shifted from its seat through the medium of the lower end 12 of the funnel 13.

45. In the modified construction shown in Fig. 4, 17 denotes the body of the receptacle and 18 the top, the latter being conoidal in

contour. The apex of the top 18 as at 19 is provided with an inlet opening closed by a screw-threaded cap, a well known construction and no claim being made thereto. The top 18 is provided with an opening 20, the wall of which is bent inwardly as at 21 forming an annular flange and also a valve seat for a globular valve 22. The reference character 23 denotes a curvilinear spout 10 having an outlet at one end and one side offset as at 25 so as to provide a pocket 26 having an inclined portion 27. The pocket 26 is adapted to receive the valve 22 when the latter is shifted off its seat, such action taking place when the receptacle is tilted to discharge the contents thereof. The spout 23 at its lower end is formed with a flange 28 through which extends the hold-fast device 29 for fixedly securing the spout 23 to the top 18. The function of the valve 22 shown in Fig. 4 is the same as that set forth in connection with the valve 5 shown in Figs. 1, 2 and 3. The spout 6 as well as the spout 23 is provided with a combined guide and stop 28 positioned in such relation with respect to the pocket 10 or the pocket 26 so as to guide the valve into the pocket and furthermore prevent the valve from shifting to the outlet 24 of the spout 23, or to the outlet 14 30 of the spout 6 as well as preventing the valve from passing out of the opening 9 when the form of spout shown in Fig. 1 is used. The combined stop and guide 30 preferably consists of a thin protuberance on the inner face of the spout.

The flanges 4 and 21 provided in the tops 2 and 18 respectively prevent the full force of the fluid from coming into contact with the valve so that the valve will not be suddenly shifted from its seat. The opening at the bottom of each of the spouts is sufficiently large to allow the valve to pass through, but the valve is prevented from dropping out through the medium of the flanges which project beyond the opening at the bottom of the spout. The pocket formed in either of the spouts provides means for receiving the valve during the act of discharging the contents so that the valve will not interrupt the discharge.

What we claim is:—

1. A receptacle provided with an opening in its top, the wall of said opening depending within said receptacle and forming an annular flange which constitutes a valve seat, a spout surrounding said opening, secured to said top and provided with a laterally extending pouring nozzle and an opening for a funnel, said opening arranged over the valve seat, and a valve mounted in said spout upon said seat, thereby closing said opening and adapted when the receptacle

is tilted for the discharge of its contents to nest in said pocket thereby preventing interruption of the discharge. 65

2. A receptacle comprising a body portion and a top said top formed with an opening having the wall thereof depending inwardly and providing an annular flange, said flange constituting a valve seat, a spout secured to said receptacle and surrounding said opening, said spout having a laterally extending pouring nozzle and an opening for a funnel, said opening arranged over the valve seat and a valve arranged in the spout and adapted to engage said seat whereby the entrance of foreign matter to the contents of the receptacle is arrested, said spout at its lower end of a diameter as to allow of the passage of the valve and said flange 80 of a diameter to arrest the movement of the valve.

3. A receptacle comprising a body portion and a top said top formed with an opening having the wall thereof depending inwardly 85 and providing an annular flange, said flange constituting a valve seat, a spout secured to said receptacle and surrounding said opening, said spout having a laterally extending pouring nozzle and an opening for a funnel, 90 said opening arranged over the valve seat and a valve arranged in the spout and adapted to engage said seat whereby the entrance of foreign matter to the contents of the receptacle is arrested, said spout at 95 its lower end of a diameter as to allow of the passage of the valve and said flange of a diameter to arrest the movement of the valve, said spout provided with an opening in its top to facilitate the positioning of a 100 funnel when filling the receptacle.

4. A receptacle provided with an opening in its top, the wall of said opening depending within said receptacle and forming thereby an annular flange which constitutes 105 a valve seat, a spout surrounding said opening secured to the top and provided with an outlet and a pocket, a valve mounted in said spout upon said seat, thereby closing said opening and adapted when the receptacle is 110 tilted for the discharge of its contents to engage in said pocket, thereby preventing any interruption of the discharge, and a combined guide and stop arranged interiorly of the spout to limit the movement of said 115 valve.

In testimony whereof we have hereunto set our hands in presence of two subscribing witnesses.
